UNITED STATES PATENT OFFICE.

BENJAMIN H. JEFFERSON, OF CHICAGO, ILLINOIS, ASSIGNOR TO HARRY H. KING,
TRUSTEE, OF CHICAGO, ILLINOIS.

INDICATOR ALARM DEVICE.

1,145,591.

Specification of Letters Patent.

Patented July 6, 1915.

Application filed October 9, 1914. Serial No. 865,784.

To all whom it may concern:

Be it known that I, BENJAMIN H. JEFFERSON, a citizen of the United States, residing at Chicago, in the county of Cook 5 and State of Illinois, have invented certain new and useful Improvements in Indicator Alarm Devices, of which the following is a specification.

My invention relates to an indicator and 10 alarm device whereby an audible alarm will be made, after the lapse of a predetermined period of time, less than one hour, for which the device may previously have been set.

One of the objects of my invention is to 15 provide, in association with an ordinary clock mechanism, means for causing an audible alarm to become effective after the lapse of a predetermined period of time, for which an index or hand has been set, by 20 turning it backward from an objective point, as for instance, from the point usually indicated on clock dials by the Roman numeral XII, whereby to vary the period of time to 25 elapse from the set point to the objective point.

Another object of my invention is to provide a silent zone on the dial into which to 30 manually move the index hand to stop the operation of the alarm mechanism and to throw out the train of gearing which serves to move said hand from the set point to the objective point.

Another object of my invention is to 35 display upon the dial, arbitrary indicia, such as the names of certain foods to be cooked, whereby to indicate the time required to cook the respective foods, so that after the lapse of the respective periods of time, to which the hand may have been 40 previously moved, an alarm will be sounded to warn the cook that the period of time for which the device has been set, has expired.

Another and further object of my invention is to simplify and improve such mechanisms whereby to render them more efficient, certain of operation and more durable.

Other and further objects of my invention will be readily apparent to persons 50 skilled in the art from a consideration of the following description when taken in conjunction with the drawing, wherein—

Figure 1 is a front elevation of the device. Fig. 2 is a side elevation with a part 55 broken away, showing part of the mecha-

nism within the casing. Fig. 3 is a rear elevation. Fig. 4 is an enlarged vertical section, taken on line 4—4 of Fig. 2. Fig. 5 is an enlarged fragmentary section, taken on line 5—5 of Fig. 4. Fig. 6 is an enlarged 60 fragmentary transverse section, taken on line 6—6 of Fig. 2. Fig. 7 is a detail of a portion of the device shown in Fig. 6. Fig. 8 is a detail of the alarm mechanism.

In all the views the same reference characters are employed to indicate similar parts.

The device, preferably, includes a mechanism 10, such as that of an ordinary clock, inclosed in a casing 11, which is secured to the back plate 22 of the frame 12, in which is positioned a glass plate 13, and which covers the dial 14. The dial 14 is divided circumferentially near its periphery into sixty equal spaces or divisions indicating minutes of the hour, over which an index, or hand 15, is adapted to be manually rotated anti-clock-wise, by a knob 16, which passes through the plate 13. Below the axis of the index 15 is another dial 17 which is shown to be imprinted on the dial 14 and which is adapted for the hour hand 18 and the minute hand 19, of an ordinary clock.

Supporting legs 20—20 are secured to each side of the frame 12, and a leg 21 is 85 secured to the rear portion of the casing 11, so that when the indicator rests upon these legs the face 14 has a slight inclination from the vertical. The plate 22 covers the back of the frame 12 and is held in place 90 as by means of screws 23. The casing 11 of the clock, is secured to this plate and the sleeve and arbor which rotate the hour and minute hands 18 and 19 respectively pass through the plate and through the dial 14. 95

Secured to the plate 22 is a bracket 24, which supports the alarm bell or gong 25, and projecting through the casing 11 is an arm 26 which carries the bell hammer 27. The arbor 28 of the clock mechanism carries 100 a minute hand 19 and the sleeve 29 carries the hour hand 18, which hands are clearly shown in Fig. 1. Secured to the arbor 28 is a gear wheel 30 and loosely pivoted to the arbor 28 is a plate 31. An arbor 32, 105 which has bearings in the bracket 33 and in another bracket 33', carries on its front end the index 15, and the setting knob 16, whereby the said arbor 32 may be freely rotated by manual operation when the index 110

is turned anti-clock-wise. Secured to the arbor or shaft 32, is another gear wheel 34, of the same size and containing the same number of teeth as the gear wheel 30. This gear wheel, 34 bears a laterally projecting pin 35, the office of which will be hereinafter more fully explained.

Loosely rotatable upon the plate 31 is a gear wheel 36 which is in constant mesh with the gear wheel 30 and which is adapted to be moved into mesh with the gear wheel 34 by the operation of the spring 37 when the pin 35 on the gear wheel 34 is not in the path of the movement of the plate 31 to produce this effect. Projecting from the edge of the plate 31 is another pin 38, more clearly shown in Fig. 7.

The verge wheel 40, of the alarm mechanism, is mounted upon a rotatable shaft 41 and is in operative relation with the verge 42, the latter being connected to the arm 26, carrying the hammer 27. Projecting from the axis of the verge 42, as from the collar 43, is another lever, or arm 44, having a laterally bent end portion 45 which normally lies against a side flange 46 carried by a wheel 47. The flange 46, of the wheel, is provided with a notch 48 through which the laterally bent end of the lever 44 will play when said notch is in register with the path described by the end of said lever. The verge wheel 40 is rotated by the usual spring mechanism while the wheel 47 is operated by the clock mechanism. The gear wheels 30, 34 and 36 being of the same dimensions, the arbor 32 will be rotated at the same number of revolutions as will the minute arbor 28 of the clock mechanism when the gear wheels 34 and 36 are in mesh so that the index 15 in making one substantially complete revolution, will travel at the same relative speed as the minute hand 19, of the clock mechanism.

When the wheel 47 is in the position shown in Fig. 8, with respect to the end 45 of the lever 44, the verge wheel 44 will vibrate the arm 26, carrying the hammer 27, and the said hammer will strike the bell 25 a number of strokes to produce the desired alarm. But if the wheel 47 be turned slightly, so that the laterally deflected end 45 of the lever 44 shall pass outside of and overlie the rim 46, or be retained inside of the rim, the verge 42 will thus be held in fixed relation with the verge wheel 44 and can no longer be moved upon its axis 43.

Assuming now that the gear wheels 34 and 36 are in mesh relation, as shown in Fig. 4. If the index hand 15 be turned anti-clock-wise, and with it the shaft or arbor 32, by means of the knob 16, which projects beyond the glass covering the face of the device, the rotation of the wheel 34, which is carried by the arbor 32, with relation to the wheel 36 is such as to move the latter out of mesh

relation therewith by moving the plate 31, slightly against the yielding spring 37, but if effort be made to manually turn the index 15 in the opposite or clockwise direction, by means of the knob 16, the gear wheel 34 will cause a wedging in of the teeth of the gear wheel 36, and rotation can not thus be made in this direction, owing to the relation of the pivotal plate 31 with reference to the gear wheels 34 and 36. Now if the rim wheel 46 be fixed upon the arbor 32 in such position that the end 45 of the arm 44, will fall into the notch 48 of the wheel 47, at the time when the index 15 is in vertical or alarm position, or when it points to the position usually indicated by the numeral XII, the alarm will be sounded, because then the notch 48 will permit the end of the lever 44 to vibrate through the notch or to pass in and out beyond the rim 46 of the wheel 47, the vibrating verge 44 will vibrate the hammer, which will strike the bell 25 a series of blows, to cause an alarm.

When the index 15 arrives at the position stated, the pin 25, carried by the gear wheel 34 is about to make contact with the plate 31, and push the plate laterally upon its pivot 28, so that the gear wheels 34 and 36 are thereby moved out of mesh, and the time mechanism of the clock will no longer rotate the gear wheel 34 and arbor 32, therefore, the hand 15 will remain in its vertical position, but the alarm will continue to be sounded for a predetermined length of time, depending upon the character of the spring, and its environments, which operates the verge wheel 40.

Upon the dial 14, it will be observed that the vertical point 0 immediately over the axis 16 of the index 15, is in a zone marked "Alarm" that is to say, this is the point at which the alarm will be sounded, when the terminal of the index hand 15 is within this zone. While the alarm is being sounded it may be stopped by rotating the knob 16 to the right, the arbor 32 being now free, until it occupies the zone marked "Silent", when the alarm will cease, because the notch 48 has been moved out from under the end 45 of the arm 44 and the rim 46 will restrain the operation of the hammer. When the index has been moved into the silent zone the pin 35 carried by the wheel 34 will thus be caused to make contact with the pin 38, which projects from the plate 31 to restrain or prevent any effort to rotate the index 15 farther to the right than the zone marked "Silent". When the index arrives at the vertical point, at which the alarm is produced, it is automatically thrown out of geared relation with the time mechanism of the clock and so remains until it has been moved anti-clock wise beyond the alarm point.

The use and operation of the device is as

follows: If it is desired that 10 minutes shall elapse before an alarm is given, the index 15 is moved to the left by means of the knob 16 until it points to the numeral 10. This operation automatically throws the index 15, into geared relation with the clock mechanism, as heretofore explained, so that said index 15 will travel or be moved, at the same relative speed as the minute hand 19, of the clock mechanism. When the index hand has arrived at the vertical point marked "Alarm" the alarm will be sounded and will call the attention of the operator to the fact that the elapsed time has passed, and the operator may then move the index 15 slightly to the right, into the "Silent" zone which operation entirely disconnects the index 15, and its moving mechanism from the clock mechanism.

20 For convenience of inexperienced cooks, each of the minutes, of the dial 14, may have associated therewith the name of some food or foods to advise the cook of the time necessary that the given food or foods should be cooked; thus to boil eggs soft, this legend is placed opposite the second minute to the left of the alarm point, indicating that if the index 15 be placed upon the minute 2, that two minutes will elapse 25 while the eggs are cooking before the index will arrive at the alarm point. Another illustration may more clearly explain the use of the apparatus in this respect. It will require 57 minutes to bake cake, therefore if 30 the index 15 be turned anti-clock-wise until it is opposite the minute 57, 57 minutes will have elapsed before the index reaches the alarm point and therefore the cook will be advised that the cake has been sufficiently 35 baked. Other indices and legends, than those shown may, of course, be used in connection with my indicator, and the device is capable of many uses without such indications.

45 It will be noticed that the minute indications on the dial 14 are in the reverse order of those on the usual clock dial.

The apparatus is adapted for and may be used to indicate at the end of any pre-determined period of time less than one hour. If the index 15 should be by oversight or accident set back too far it may be moved forward by rotating the usual hand setting knob 50 which moves the hands 18, 55 19 of the clock mechanism, accordingly, and after the index 15 has been placed at the point of alarm it will be rendered thereby further inoperative, and then the hands 18 and 19 may be set back to their former 60 positions by means of the knob 50 and the index 15 may be set back again to any selected point on the dial in the manner heretofore described.

While I have herein shown a single embodiment of my invention for the purpose

of clear disclosure, and have described the particular exemplification; it must be understood that considerable change may be made from the particular arrangement and disposition of the parts, within the scope 70 of the appended claims.

Having described my invention, what I claim is:—

1. In a device of the character described, the combination with a clock time mechanism, of a dial divided into minutes of an hour indicated by numerals increasing in value in anti-clock-wise direction from a given point; an index movable in co-operation therewith; means for automatically 75 connecting said index with said time mechanism when said index is manually moved anti-clock-wise over said dial from said given point to a selected position; and automatically to disconnect said index from said time mechanism, when it is returned to said point by said mechanism and means to sound an alarm when said index arrives at said point.

2. In a device of the character described, 90 the combination of a clock time mechanism and a dial and hands therefor; of a larger dial surrounding the clock dial, divided into minutes of an hour indicated by numerals increasing in value anti-clock wise from a given point; an index movable in co-operation 95 with the larger dial; means for automatically connecting said index with said time mechanism when said index is manually moved anti-clock wise over said larger dial from said given point; and automatically to disconnect said index, from said time mechanism, when it is returned to said point by said mechanism; means to sound an alarm when said index arrives at said 100 point, and means to lock the index when it arrives at a given point beyond the alarm point.

3. In a device of the character described, 110 the combination with a clock time mechanism a dial and hands therefor; another dial divided into minutes of an hour indicated by numerals arranged in the reverse order from that of a clock; an index movably co-operating with said latter dial; a designated 115 point on said dial indicative of alarm; means for manually moving said index over said dial in anti-clock-wise direction to any selected minute space; audible indicating mechanism operable when said index arrives at said alarm point; and automatic means to connect said index with the clock time mechanism when said index is manually moved from said alarm point and automatically to disconnect said index from 120 said time mechanism at or about the time when said index arrives at said alarm point.

4. In a device of the character described, the combination with a clock time mechanism, a casing, a clock dial and hands there- 130

for; of a dial frame, to the rear of which said clock casing is connected; an index dial within said frame, divided into minutes of an hour indicated by numerals arranged in the reverse order of a clock; an index movably coöperating therewith and having its axis substantially within the center of said index dial, said clock dial being positioned at one side of the axis of said index dial; a 10 zone on said index dial indicative of alarm; another zone on said index dial indicative of silence; means, automatically to connect said index with said clock time mechanism, when said index is moved anti-clock-wise 15 out of said alarm zone and automatically to disconnect said index from said clock time mechanism when it arrives at the alarm zone; means to produce an alarm when said index reaches said alarm zone; and to stop the 20 alarm when said index is manually moved into the silent zone and means to prevent further manual movement of said index in the same direction.

5. In a device of the character described, 25 a pivoted lever carrying a hammer on its free end; a rotatable wheel, means secured to the lever, near its pivotal point for vibrating said lever in coöperation with said wheel; another rotatable wheel provided 30 with an annular flange having a notch or opening therein; another lever projecting from the pivotal point of the first named lever, having a part adapted to pass through said opening to permit the hammer to be 35 vibrated and to lock said vibratory means when on either side of said flange.

6. In a device of the character described, 40 a pivotal lever carrying a hammer on its free end, to sound an alarm; a rotatable toothed wheel; a verge, secured to the lever near its pivotal point for vibrating said lever, in coöperation with said wheel; another rotatable wheel provided with an annular, laterally projecting flange having a 45 notch, or opening therein; another lever projecting from the first named lever having a part normally in contact with one or the other side of said flange, adapted to pass through said opening to permit the hammer to be 50 vibrated and to lock said verge against movement, to prevent vibration of said hammer, when on either side of said flange.

7. In a device of the character described, 55 a pivoted lever, carrying a hammer on its free end to sound an alarm; a rotatable, notched wheel; a verge secured to the lever, near its pivotal point for vibrating said lever, in coöperation with said wheel; a 60 clock time mechanism; another wheel, to be rotated by said time mechanism, provided with an annular, laterally projecting flange having a notch or opening therein; another

lever, projecting from the pivotal point of the first mentioned lever, and having a laterally deflected part normally in contact with one or the other side of said flange adapted to pass through said opening and permit the hammer to be vibrated and to lock said vibratory verge when on either side of said flange.

8. In a device of the character described, the combination of a rotatable toothed wheel; a pivoted vibrating mechanism, operatively associated therewith; a hammer arm projecting from said mechanism; a wheel 75 having a flange provided with a slot associated with said device and a control arm secured to said mechanism the terminal whereof normally lies on one side or the other of the flange of the wheel to restrain 80 said mechanism; said slot when registering with the control arm permitting free movement of the vibrating mechanism.

9. In a device of the character described, 85 the combination with a clock time mechanism; of an arbor; an index hand carried thereby; a dial in coöperation therewith; a wheel, provided with a flange having a notch therein, secured to said arbor, with said notch in substantially the same plane as 90 the index; an alarm mechanism having a restraining arm, the free end of which normally rests against either side of said flange to restrain said alarm mechanism and which releases said alarm mechanism when the 95 notch is in the path of its movement.

10. In a device of the character described, the combination with a clock time mechanism; of an arbor; an index hand carried thereby; a dial in coöperation therewith; a 100 wheel, provided with a flange having a notch therein, secured to said arbor, with said notch in substantially the same plane as the index; an alarm mechanism having a restraining arm, the free end of which normally rests against either side of said flange to restrain said alarm mechanism and which releases said alarm mechanism when the 105 notch is in the path of its movement; a train of gearing operable when the notch of said 110 wheel is moved out of the path of said arm, to connect said arbor with said clock time mechanism and means to disconnect said gearing about the time when the notch is moved into register with said restraining 115 arm.

In testimony whereof I hereunto set my hand in the presence of two subscribing witnesses.
